(57) CLAIM

The ornamental design for a picnic backpack, as shown and described.

DESCRIPTION

FIG. 1 is a front and top perspective view of a picnic backpack, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of a portion of the picnic backpack indicated with numeric 9 in FIG. 1; and,

FIG. 10 is an enlarged view of a portion of the picnic backpack indicated with numeric 10 in FIG. 1.

The broken lines in the figures illustrate portions of the picnic backpack that form no part of the claimed design. The dash dot dash lines in FIGS. 1, 9 and 10 are for the purpose of depicting the cut line of the enlarged views and form no part of the claim.

1 Claim, 10 Drawing Sheets
